GEORGE R. SIEFKEN, OF NEW YORK, N. Y.

VENTILATING DEVICE.

Application filed June 3, 1926. Serial No. 113,436.

The invention relates to ventilating apparatus for use in buildings, railroad cars, and like structures, and has to do more particularly with apparatus by which atmospheric air may be admitted to the structure in regulated amounts and without the production of currents of high velocity, commonly referred to as drafts. The improved ventilating apparatus of this invention is further arranged so that the air admitted may be mingled with the air within the structure in such a way that good diffusion is secured and the fresh air is distributed to all parts of the structure, or room.

The improved apparatus is adapted particularly to be built in the wall of the structure prior to its completion and it may be placed at any point in the wall. Preferably, the ventilator is placed beneath the frame of a window, so that it is not necessary to cut or leave a special opening in the wall for the ventilator, but simply to make the usual window opening slightly greater than required by the size of the window to be used.

Also, it is desirable to place the ventilator above the heater in the room, if such heater is present, since the upwardly rising current of heated air flowing from the heater may conveniently be utilized in the diffusion and mingling of the fresh air. As heating devices such as radiators are commonly placed beneath windows, the building of the ventilator in the structure wall beneath the window frame is not only a matter of convenience and cheapness, but also affords the best results in most installations.

The ventilating apparatus of this invention includes a chamber preferably built in the structure wall and having an opening through which atmospheric air may enter the chamber, and another opening through which the air may pass from the chamber into the room. These openings are placed out of alignment so that the air passing through the chamber into the room flows along a tortuous path and direct currents are prevented. Within the chamber, and at a distance from both openings, is a control device for regulating the amount of air admitted, and this device is so arranged that the air flow changes direction after its passage through the device. Such changes of direction result in diffusion of the air, preventing the formation of currents of high velocity, even though there is a high wind pressure against the wall of the structure.

The control device is preferably automatic in operation and arranged to admit air through an opening or openings, the size of which is variable in accordance with outside wind pressure.

The opening through which air is discharged into the room is preferably provided with a diffusion screen by which the direct air flow is broken up and the tortuous passage of the air through the chamber, together with the action of the screen, reduces the air velocity to a material extent and even though the fresh air is permitted to enter the room only through a small opening, it is discharged through an opening of much larger cross-section and its velocity thus cut down. The air current entering the room flows upwardly from the discharge outlet along a wall, and as the air is normally colder than that within the room, convection currents are set up which promote the distribution and mixture of the fresh air with that present. When the room is heated by a heater which is placed beneath the ventilator, further advantageous results are obtained since the upwardly moving current of heated air blankets the fresh air between it and the wall and the two streams flow side by side until the cold air has been heated and diffusion and distribution are obtained.

For a better understanding of the invention, reference will be made to the accompanying drawings, in which

Fig. 1 shows a view of a portion of the outer wall of a structure in which the ventilating apparatus is installed,

Fig. 2 is a vertical section through the wall and the apparatus,

Fig. 3 is a similar view of a modified form of construction,

Figs. 4 and 5 are views similar to Fig. 3, but showing further modifications, and

Figs. 6 and 7 are top views of the discharge outlet showing diffusion screens of different types.

Referring now to the drawings, the ventilating apparatus is illustrated for convenience as being built in the wall of a building beneath the window frame. It is not necessary that the apparatus be placed in this position, but such an arrangement is convenient because the apparatus can be built in prior to the completion of the building and before the frame is put in position. With such an installation, therefore, the usual window opening is made but it is slightly

larger than that required by the size of the window and the ventilating apparatus is placed beneath the window frame.

The window frame 10 having the window 5 sash 11 of the usual construction, rests on the top of a chamber 12. This chamber has an opening 13 protected by a screen 14 against the entrance of dirt. The opening permits atmospheric air to enter the chamber. The chamber extends entirely through 10 the wall and at its inner end is provided with an opening 15 through which the fresh air may enter the room. This opening is preferably placed so that it discharges a stream of air vertically along the inner wall 15 of the room, as indicated in Figs. 2, 3, and 4, although, if desired, the stream may enter the room through an opening arranged to discharge it horizontally, as shown at 16 in Fig. 5. The opening 15 may be formed 20 in an extension 17 from the chamber, as shown in Figs. 2 and 4, or the opening may be formed by cutting away the top wall of the chamber as at 18 and forming the opening 25 in the window frame, as indicated at 19. The construction illustrated in Fig. 3 discharges the current of air vertically into the room, but this current is discharged within the window opening, rather than free 30 of the latter along the inner surface of the wall. The arrangement illustrated in Fig. 3 may, in some instances, be more desirable than that shown in Figs. 2 and 4, since the extension 17 projecting beyond the inner face 35 of the wall of the building is not used with that arrangement.

In both types of construction illustrated, a diffusion screen 20 may be employed. Screens or grilles as shown in Figs. 6 and 7 are satisfactory for the purpose, and various other types of convenient construction 40 may also be employed. These screens or grilles serve to intercept the current of air passing through the chamber and to break it up so that a direct current of high velocity 45 is avoided.

Within the chamber, and at a distance from the openings 13 and 15 is a control 50 mechanism here illustrated as of the automatic type, operating to admit air in quantities dependent upon the outside wind pressure. The chamber is provided with a horizontal partition 21 having openings 22. Each of the openings is controlled by a valve 23 movable on a vertical rod 24, the lower end of which is supported in a horizontal bar 25. There are a number of these 55 openings formed in the partition arranged in rows extending lengthwise of the chamber, and the valves are free to move up and down 60 on the rods 24. Each valve, of conical form with its apex at the top, is suitably weighted, and the weights 23' of the different valves 65 are graduated in value so that as the wind pressure increases the valves will be held

successively against the under surface of the partition 21, so as to close the openings. When there is a low wind velocity all of the valves will be open, and as the wind velocity increases more and more of the valves are 70 closed, so that the amount of air entering the room is thus regulated.

The control mechanism is placed within the chamber at a distance from the opening through which the air enters and control outlets through which the air leaves the main body of the chamber and enters a smaller portion thereof designated 20^a which may be termed the diffusion chamber. The air flowing through the outlets controlled by the automatic devices flows upwardly into the diffusion chamber, striking the upper wall thereof and being deflected and flattened out in a wide thin stream which then flows horizontally through the chamber 20^a, and either directly into the room, as in the form shown in Fig. 5, or else upwardly through the vertical passages to enter the room through the diffusion screens 20. The automatic mechanism is preferably arranged so that there 80 are a plurality of dampers controlled by weights which act at different air pressures, the dampers being successively closed as the air pressure increases. When there is a relatively high wind blowing, all but one of the dampers for example may be closed. The air entering the room then flows through this damper in the form of a relatively fine stream which, if allowed to enter the room directly, would result in a draft which 85 would not only be unpleasant, but would also interfere with the proper diffusion of the fresh air through the room. With the arrangement illustrated, this small stream of air cannot directly enter the room 90 but enters the diffusion chamber 20^a, where it is flattened out, its velocity reduced greatly, owing to the changes in direction which the air must make before it finally enters the room, and instead of a fine stream of air 95 of substantially circular cross-section, there is a wide thin stream which gives the best 100 ventilating effect.

The chambers in the different forms of apparatus are accessible from the inside of 115 the room through openings closed by slides or doors 26 so arranged that the interior of the chamber may be cleaned whenever necessary. The automatic mechanism may be installed so as to control air flow under all 120 ordinary conditions and by a proper selection of the weights, the mechanism will regulate the areas through which air may enter the room in accordance with the wind velocity outside the building.

When the ventilating apparatus is used to admit air into a room which is heated by the usual heating devices, it is desirable to place the ventilator so that it discharges fresh air 125 into the room along a wall at a point above

- a heating device. Heating radiators are ordinarily placed beneath windows and with the constructions shown in Figs. 2 to 5 inclusive, a current of air in the form of a 5 wide thin stream enters the room along a wall above the radiator. A current of heated air from the radiator flows up along the wall and this heated current, also in the form of a wide sheet, blankets the cold air 10 current and the two streams flow side by side upwardly until the cold air is warmed and diffused and mingling of the fresh air and the air within the room is accomplished. This arrangement also results in the production 15 of convection currents which cause a rapid distribution of the fresh air throughout the room. By building the ventilating device in the wall of the building, in the manner illustrated, there are no parts which 20 project beyond the wall to an undesirable extent, and as the interior of the chamber is readily accessible, the ventilator is easily cleaned and the control mechanism kept in working condition.
- 25 I claim:
1. A ventilator for admitting air into a room comprising a chamber having an opening for admitting air from outside the room, a diffusion chamber having substantially horizontal and vertical connecting passageways, the vertical passageway opening into the room, the lower wall of the horizontal passageway having an opening through which 30 air from the first named chamber may be admitted to said diffusion chamber, automatic 35 means for controlling the flow of air through said opening, said opening being located at a point beneath the upper wall of the horizontal passageway whereby the air passing through said opening is caused to impinge 40 upon said upper wall and become diffused and have its direction of travel changed before passing through the vertical passageway into the room.
  2. In a ventilator for admitting air into a room comprising a chamber having an opening for admitting air from outside the room; a diffusion chamber having a substantially horizontal passageway and a substantially vertical passageway, said vertical passageway having one end thereof communicating with the horizontal passageway at one end of same, and having its other end communicating with the atmosphere within the room, the lower wall of 45 the horizontal passageway having at least one opening through which air from the first-named chamber may be admitted into the diffusion chamber, automatic means for controlling the flow of air through said 50 opening, said opening being located beneath the upper wall of the said horizontal passageway, whereby the air passing there-through is caused to impinge against said upper wall and become diffused before traversing said horizontal passageway and entering the vertical passageway from which it passes into the room.

In testimony whereof I affix my signature.

GEORGE R. SIEFKEN.
